UNITED STATES PATENT OFFICE.

ELMER JAMES, OF PROVO, UTAH.

ORE SEPARATOR.

Application filed March 14, 1923. Serial No. 624,964.

To all whom it may concern:

Be it known that I, ELMER JAMES, a citizen of the United States, residing at Provo, in the county of Utah and State of Utah, 5 have invented certain new and useful Improvements in Ore Separators, of which the following is a specification.

My invention relates to mining machinery, and has for its object to provide an 10 economical ore separator, whereby the valuable minerals may be separated from the gangue, whether such mineral be of such light specific gravity as to float on or in water, or whether it be of greater specific 15 gravity and will sink in water.

A further object is to separate the lighter from the heavier minerals in order that the lighter minerals may be subsequently treated by one process, and the heavier minerals 20 may be subsequently treated by other processes.

These objects I accomplish with the machine illustrated in the accompanying drawings, in which similar letters and numerals 25 of reference indicate like parts throughout the several views, and as described in the specification forming a part of this application and pointed out in the appended claims.

In the drawings in which I have shown 30 a substantial embodiment of my invention Figure 1 is a side elevation of the machine, parts cut away and parts in section. Figure 2 is a fragmentary view in longitudinal section of the junction point between the 35 two cylinders. Figure 3 is an end elevation of the junction end of the first cylinder. Figure 4 is a plan view of the machine. Figure 5 is a longitudinal diametrical section of the gangue discharge end of the machine, some of the discharge openings shown 40 in dotted lines. Figure 6 is a transverse vertical section on line 6—6 of Figure 4, looking in the direction of the arrows. Figure 45 7 is a transverse vertical section on line 7—7 of Figure 4 looking in the direction of the arrows.

In separating the valuable minerals from the gangue in which they are found it is frequently ascertained that some of the valuable minerals are coated with oil and other substances which will cause them to float in water or on the surface thereof, while other portions of the valuable minerals in the same ore are not so coated and may be 50 caught by mechanical concentration. The

present invention is intended for use in and under such conditions whereby the ore, suitably crushed to release the minerals from the gangue, is driven through two co-acting cylinders by a flow of water and while passing through said cylinders the crushed ore is agitated by mechanical and hydraulic means, and thereby the coated minerals are floated out at one end of the cylinders and are there caught, while the uncoated minerals are carried out at the opposite end of said cylinders and caught, and the gangue allowed to pass out at the end first mentioned where the coated minerals are caught. I thus utilize three well-known principles 70 of separating minerals from gangue; namely, hydraulic washing and agitation, flotation and concentration, in one machine, thereby economizing in time, space in which to operate and machinery required to save 75 the values.

Referring to the drawings: An angle iron supporting frame is provided comprising uprights 1 and longitudinal beams 2 and 3, and cross beams 4 and 5. Two co-acting cylinders A and B are mounted within said frame and they are connected by a universal joint in order that one end of the cylinder A may be moved vertically up and down without disconnecting the opposite 85 end from the cylinder B. To make said adjustment the said cylinder A is supported within the main frame by a supporting rack consisting of the longitudinal beams 6 and cross ties 7, and the suspending arms 8 at 90 one end, with the U-shaped loop 9 at the opposite end. The legs of the said loop 9 are pivoted to the beams 6, and said loop is suspended from the cross-head 10 by the threaded rod 11 which is fastened to the upper end of said loop 9. An internally threaded hand wheel 12 whose threads mesh with the threads of said rod 11 is the means I use to raise and lower the front end of 95 said cylinder A. The rear end of said supporting rack is carried on pins 13 which are secured in the uprights 1 adjacent the meeting ends of the cylinders by the said supporting arms 8 engaging with said pins 13. The said cylinders A and B rest on the 100 wheels 14 and 15 respectively with their respective shafts 16 and 17. Power to rotate said cylinders is applied through the sprocket gear 18 which is secured on said cylinder B and any power may be supplied through 110

a sprocket chain, not shown, to drive said sprocket gear 18. I provide a screw feed which enters the cylinder A at raised or front end thereof, and which consists of the 5 commonly used worm screw 19 within the tube 20 with a power driven gear 21, by which said screw 19 is rotated. The said screw feed terminates about eighteen inches from the rear end of said cylinder A, and 10 the ore is dumped out of the feed at that point, and that is where the separation commences. A spray pipe 22 enters the raised and front end of said cylinder A and is perforated throughout its length with small 15 openings through which water is supplied to spray the interior of said cylinder A and supply the water within both cylinders and by which the ore is moved and separation is effected. On the lower and meeting end 20 of said cylinder A an inwardly turned flange 23 is provided having a projecting tube 24 integrally formed thereon. The meeting end of the cylinder B has an annular end or closing plate 25, the opening 25 therein coinciding with the tube 24, in order that said tube may be passed partially through and operate within said closure plate 25. Adjacent and parallel with said closure plate 25, an annular baffle ring or 30 band 26 is fastened in said cylinder B. An annular closure plate or inwardly turned flange 27 partially closes the rear end of the cylinder B, and a thimble 28 is secured in said plate, through which the floating mineral particles are carried by a flow of 35 water. Near the rear end of said cylinder B the discharge or egress openings 29 are cut in the wall of said cylinder, and a U-shaped yoke or seal 30 is carried around 40 the end portion of said cylinder to close a portion of said discharge openings 29, and leave the others open. The lower arms of said yoke or seal 30 terminate below the water level in the cylinder in order that 45 any discharge through the openings 29 must be from those openings which are under the water, thereby allowing all floating particles of mineral to pass out with the water flowing through said thimble 28. The said yoke 50 or seal 30 is suspended from an arm 31, which is fastened to the nearest cross beam 5. The uniting mechanism connecting the cylinders A and B consists of a trunnion sleeve 34, having open slots 32 cut therein, 55 in which is operated radial lugs or trunnions 33 that are fastened to said cylinder A, and a similar pair of extended trunnions 35 are secured on the meeting end portion of said cylinder B. On the interior wall of 60 said cylinder A are secured a plurality of spirally disposed riffles 40 at an angle counter to the rotation of said cylinder. The height of the riffles for the most of the length of said cylinder is less than the other 65 portion, preferably I have found that for

three-fourths of the length of the cylinder riffles extending radially inward one-fourth of an inch do the best work, while for the other one-fourth, riffles of the depth of one and one-fourth inches are best. The cylinder 70 B is also provided with spiral riffles 41 which are given an angle in accord with the rotation of said cylinder B, with the riffles having inward radial depth of one and one-half inches. One of the purposes of 75 the riffles in cylinder A is to move the concentrates toward the front or inlet end of that cylinder, while the riffles in the cylinder B move the material to the discharge openings 29. Any tendency to form eddies 80 in the flow of the water through the thimble 28 by the gangue discharging through openings 29, will be broken up by the portion of the thimble inside the cylinder B.

The operation of my machine is as follows:—

The crushed ore is pushed into the cylinder A by the screw feed, and water under pressure is conducted through the spray pipe 22. The rotation of both cylinders and the 90 flow of water will agitate the ore and move the gangue through the cylinders. The heavier particles of mineral will be caught in the riffles 40 in cylinder A and be carried back up the incline of that cylinder and 95 dumped out of the same or front end of that cylinder. The rotation of the cylinders and spraying action of the water will tend to separate the minerals from the gangue. The gangue and all light or coated mineral 100 particles will pass through the tube 24 into the cylinder B where the agitation is continued by the riffles 41 and the rotation of that cylinder. The coated, light and floating mineral particles will be carried in suspension in and on the water and will flow out through the thimble 28, while the gangue will pass out through the uncovered openings 29 and be carried away as waste. The rate at which the ore may be treated is 105 regulated by the tilt of the cylinder A which is accomplished by turning the hand wheel 12.

Having thus described my invention I desire to secure by Letters Patent and claim:—

1. An ore separator comprising an inclined rotatable cylinder; a plurality of spiral riffles on the inner face of said cylinder inclined counter to the rotation of said cylinder; means to feed ore into the lower portion of said cylinder; an annular band partially closing the lower end of said cylinder; another cylinder operatively connected with and rotated by said first cylinder; a concentrically positioned tube connecting said cylinders; a sealing yoke partially closing the discharge from said second cylinder; a spray pipe in the first mentioned cylinder to spray the interior thereof and means to rotate said cylinders; and a yoke to 115

close all of the gangue discharge openings above the water level in the last or horizontal cylinder.

2. In a machine of the class described the combination of an adjustably inclined cylinder and a horizontally disposed cylinder operatively connected; means to feed ore into the incline cylinder near the junction of said cylinder; a plurality of spirally disposed riffles on the inner face of said cylinders; a spraying means in the first men-

tioned cylinder; annular gates partially closing both of said cylinders; tubular members in said gates to form discharge chutes from said cylinders, and openings 15 in the wall of the horizontally disposed cylinder for gangue discharge; means to rotate said cylinders; and a yoke to partially seal the discharge from the horizontal cylinder.

In testimony whereof I have affixed my 20
signature.

ELMER JAMES.
